PUNCHING DEVICE

Carl F. Lehmeier, Santa Monica, Calif., assignor
to Douglas Aircraft Company, Inc., Santa Monica, Calif.

Application February 7, 1944, Serial No. 521,450

11 Claims.

(Cl. 164—94)

This invention relates to a punching device of the type in which the punch, stripping means, and die are assembled in a holder which can be quickly clamped in adjusted position on the bed of a power press, and which is believed to be an improvement on the punching devices disclosed in the patents to Wales, Nos. 1,955,866, 2,163,651, and 2,323,431.

One object of my invention is to provide a punching device which will shorten the time required to set up a series of punching devices in a power press with the punches in precise vertical alignment with the corresponding openings of a template.

Another object is to provide a punching device in which the holder can be readily shifted or removed for replacing a broken punch, die or stripping means, without disturbing the adjacent holders or the template.

Another object is to provide a punching device in which the punches of a plurality of adjacent holders can be quickly aligned with the corresponding openings of a template, regardless of whether said openings are in a straight line or are offset varying distances from either side of a straight line.

Another object is to provide a punching device with a die having means projecting from the bottom thereof for aligning the punch with the corresponding opening in the template.

An additional object is to provide a simplified form of die, punch, and stripping means, so that any element of the set can be readily replaced, either in the event of breakage, or for substituting a different set in the holder for punching an opening of a different size or shape.

It is also an object of my invention to provide a punching device in which the aligning means of each punching device remains associated with the corresponding opening in the template during use for facilitating setting up or replacing the devices by unskilled and inexperienced operators.

A further object of my invention is to provide an improved and simplified form of holder, punch, stripping means and die which can be manufactured economically.

In the drawing:

Figure 1 is a perspective view of the punching device secured in place on a conventional power press bed.

Figure 2 is an end elevation of Figure 1, with the ram added.

Figure 3 is a vertical section view on the longitudinal center line of the device.

Figure 4 is a horizontal sectional view on line 4—4 of Figure 3 with the template removed.

Figure 5 is a vertical sectional view on line 5—5 of Figure 3, and

Figure 6 is an enlarged view in section of the aligning means of a punching device of the present invention showing the aligning means disposed in an opening of the template.

In Figure 2, the punching device 10 is shown secured between the ram 11 and bed 12 of a conventional power press, the details of which constitute no part of my invention, since any form of power press to which the device can be bolted or clamped may be employed. The punching device 10 comprises a holder 14, a punch 16, a die 18, a stripper spring 20, and a conventional fastening bolt 23. The head of the fastening bolt 23 is slideable along either of the slots 13 for adjustably positioning a device on the bed 12.

20 The holder 14 comprises a lower die supporting member 24 and an upper supporting member 36 for the punch 16 and spring 20. The lower supporting member 24 is provided with an elongated vertical slot 25 for receiving the fastening bolt 23 to the end that the holder may be slidably adjusted transversely of the bed. The supporting member 24 is formed with a recess 26 in its bottom face to accommodate a template 27 which is retained in clamped position between said arm 24 and bed 13.

25 The front portion of the recess is more shallow than the intermediate portion, and has a depth substantially equal to the thickness of the template 27. The template 27 may be of any desired form but is shown as a flat sheet provided with openings 28 accurately located with respect to each other. In order to reproduce the template openings 28 in the same relative position in the work to be punched, the punches 16 and dies 18 must be precisely aligned with the template openings 28, which required considerable time by an experienced operator in prior art devices. The use of my device simplifies the aligning operation, and is especially useful whenever it becomes necessary to replace a broken punch, or to substitute 30 a punch and die set for a different size or shape of opening.

35 As shown in Figures 2 and 3, the die 18, preferably made cylindrical in shape, is provided with a locating lug 29 projecting from its bottom face for entering template openings 28, and with a die opening 30 in its upper end, the die opening 30 communicating with recess 31 for disposing of the scrap pieces, and being aligned vertically with lug 29. The lower end of the die 18 is made larger in diameter than the upper end to provide 40 45

a shoulder 33, which coacts with a stop shoulder 34 formed in the free end of arm 24 by making the upper portion of vertical bore 35 smaller than the lower portion. The enlarged lower end of the die 18 is firmly held against vertical movement by said stop shoulder 34 when the bottom face of the die 18 is clamped against the upper face of the template 27, while the retention of lug 29 in a template opening 28 assists the fastening bolt 23 in preventing lateral movement of die 18 and holder 14.

As shown in Figures 2, 3, and 5, the upper supporting member 36 has vertically spaced arms 37 and 38 at its front end, said arms being provided with vertically aligned bores for slidably mounting punch 16 in vertical alignment with die opening 30 and locating lug 29. A stripping spring 20 surrounds the punch 16 for lifting the punch bit out of the perforation formed in the work by the punching operation. In order to accomplish its lifting action, the lower end of spring 20 abuts against the upper face of lower arm 38, while the upper end abuts against a drift pin 39 extending through the punch 16 and normally seating in aligned semicircular recesses 40 in the lower face of the upper arm 37.

In the operation of my invention as many punching devices 10 will be employed as there are holes to be punched in the work. The template 27, with the openings 28 accurately located in the same relative position as the holes which are required to be punched in the work, is placed on the bed 12 of a power press. A punching device 10 for each opening 28 is then readily clamped or bolted to the bed 12 the template being clamped between the under-surfaces of the supporting member 24 and the top surface of the bed, with the lug 29 on the bottom face of each die 18 located in its corresponding opening 28 in the template 27. The template will be securely held against movement when all of the punching devices have been secured in place. The work (not shown) is now placed on top of the adjacent die members 18, against conventional stop members (not shown) if necessary, and the press is operated to force the ram 11 down on the punches 16 against the combined resistance of the springs 20 until the work is perforated. The ram 11 is then withdrawn, the springs 20 strip the punches 16 from the work by lifting against the drift pins 39, and the work is replaced.

As the template is clamped against the top surface of the bed by the punching devices of the present invention, a punching device can be removed without disturbing the template for the remaining punching devices will securely hold the template against movement. Thus the operation of again aligning the template after a punching device is removed, as is necessary with previously proposed devices, is obviated. This feature of the invention greatly reduces the time of any operational run for it not only eliminates the necessity of re-aligning the template, which must be done by a skilled operator, but also permits relatively unskilled operators to be assigned to the press.

The claims are intended to cover all changes and modifications which may be fairly regarded as coming within their scope.

I claim:

1. A punching device comprising a holder; a punch, a stripping means, and cooperating die means assembled in the front portion of said holder; the front portion of the bottom face of said holder being recessed for receiving a tem-

plate; a die opening in said die means; and means projecting from the bottom of said die means and into said recessed portion of said holder for aligning the punch and die opening with the corresponding opening in the template associated with said holder.

2. A punching device comprising a holder having an upper supporting member and a lower supporting member; the front portion of said upper supporting member carrying a punch and a stripping means; the front portion of the bottom face of said lower supporting member being recessed for receiving a template; a vertically disposed elongated slot in said lower supporting member for adjustably receiving an attaching means; and cooperating die means carried by the front portion of said lower supporting member.

3. A punching device comprising a holder having an upper supporting portion and a lower supporting portion; the front portion of said upper supporting member carrying a punch and a stripping means; the front portion of the bottom face of said lower supporting portion being recessed for receiving a template; cooperating die means carried by the front portion of said lower supporting member; a die opening in said die means; and means projecting from the bottom of said die means and into said recessed portion of said lower supporting member for aligning the punch and the die opening with the corresponding opening in the template associated with said holder.

4. A punching device comprising a holder having an upper elongated punch supporting member and a lower elongated die supporting member, the front and intermediate portion of the bottom face of said lower supporting member being recessed for receiving a template; a vertically disposed elongated slot extending through the intermediate portion of said lower supporting member for adjustably receiving an attaching member; and a vertically disposed hole in the front portion of said lower supporting member for receiving said die.

5. A punching device comprising a holder having an upper punch supporting member and a lower die supporting member; the front and intermediate portion of the bottom face of said lower supporting member being recessed for receiving a template; a vertically extending bore in the front portion of said lower supporting member; and a vertically disposed cylindrical die member in said bore, said die member having a die opening in its upper end and a downwardly projecting lug on its lower end aligned with said opening, said lug projecting into said recessed portion for aligning the punch and die opening with the corresponding opening in the template associated with said holder.

6. A punching device comprising a holder having an elongated upper supporting member and a lower elongated die supporting member; the front portion of said upper supporting member having vertically spaced arms projecting horizontally therefrom for supporting a punch; the front and intermediate portion of the bottom face of said lower face being recessed for receiving a template; a vertically disposed elongated slot extending through the intermediate portion of said lower supporting member for adjustably receiving an attaching member; and a vertically extending bore in the front portion of said lower supporting member for receiving a die means in vertical alignment with the punch, the lower portion of said bore being enlarged to provide a stop shoulder intermediate the length of said bore.

7. A punching device comprising a holder; cooperating punch and die means carried by said holder; means projecting below the lower surface of said holder for aligning the punch and die means with a corresponding opening in a template; one portion of said holder being adapted to engage the surface of said template and another portion being adapted to engage the bed plate of a press; and retaining means to draw said holder towards said bed plate whereby said template is clamped between said holder and said bed plate to align said punch and die means with the opening in the template. 10

8. A punching device as claimed in claim 7, in which said first and second portions of said holder are in spaced substantially parallel planes to accommodate the thickness of the template clamped between the holder and the bed plate. 15

9. A sheet material perforating apparatus for use between the bed and ram of a press, comprising a holder having a base and an upper head, and a perforating device mounted on said base and head and adapted to form holes in a sheet placed between base and head upon moving said bed and ram one relatively to the other, said perforating device comprising a lower die mounted to said base and a punching unit slidable vertically in a guide opening in said head and having a punch adapted to cooperate with said die; means having a predetermined position relative to said die and extending below the underneath surface of said base for locating said punching unit and die in a predetermined position relative to an opening formed in a template disposed beneath said base; and means for clamping the template between the underneath surface of said base and the upper face of said bed. 20 25 30 35

10. A sheet perforating apparatus for use between the bed and ram of a press, comprising: a holder having a lower base and an upper head, and a perforating device mounted on said base and head and adapted to form holes in a sheet placed between said base and head upon moving said bed and ram one relatively to the other, said perforating device comprising a die mounted to said base and a punching unit slidable vertically in a guide opening in said head and having a punch adapted to cooperate with said die, the underneath surface of said base being formed with horizontally spaced parallel faces vertically separated a distance equal to the thickness of a template to be mounted between said base and the bed of the press; means projecting below the upper face of the underneath surface of said base for aligning the punch and die with a corresponding opening in said template; and means for clamping the base to the bed of the press with the template therebetween. 15

11. A punching device for use between the bed and the ram of a press comprising a holder; a punch, a stripping means, and cooperating die means assembled in said holder, said holder having a face displaced downwardly from the lower surface thereof for supportingly engaging the bed of said press; and means projecting below the lower surface of said holder a distance substantially equal to the distance between the lower surface of said holder and the downwardly extending face for aligning the punch and die with a locating opening in a template placed between said lower surface and the bed of said press. 20 25 30 35
